AUDIO VISUAL WORK DESK FOR DENTAL INSTRUCTION

David C. Jenkins and Lawrence M. Levin, Burlington,
Ontario, Canada, assignors to Cox Systems Limited,
Stoney Creek, Ontario, Canada

Filed July 24, 1972, Ser. No. 274,773

Term of patent 14 years

Int. Cl. D24—01
U.S. Cl. D24—1 B

FIG. 1

FIG. 2

FIG. 3

FIG. 1 is a front perspective view of an audio visual work desk for dental instruction showing our design;

FIG. 2 is a rear perspective view; and

FIG. 3 is a front perspective view taken from the left in FIG. 1.

We claim:

The ornamental design for an audio visual work desk for dental instruction, substantially as shown and described.
